UNITED STATES PATENT OFFICE.

BENJAMIN P. REMY AND FRANK I. REMY, OF INDIANAPOLIS, INDIANA.

IGNITER FOR GAS ENGINES.

Application filed September 30, 1921. Serial No. 504,306.

To all whom it may concern:

Be it known that we, BENJAMIN P. REMY and FRANK I. REMY, respectively, citizens of the United States, and residents of Indianapolis, county of Marion, and State of Indiana, have invented a certain new and useful Igniter for Gas Engines; and we do hereby declare that the following is a full, clear, and exact description thereof, reference being had to the accompanying drawings, in which like numerals refer to like parts.

This invention relates to a low tension electric igniter of that type adapted for use on internal combustion engines for creating the spark whereby the gas charges will be ignited.

The main feature of the invention lies in the bearings of the igniter in which the movable electrode shaft is mounted, and especially a bearing in the igniter block which is provided with a reduced bearing surface therein. Heretofore difficulty has been had with magnetos of this type in the igniter because of carbon forming in the bearings and causing the electrode shaft to stick and become clogged so that no spark would be produced. It has been found that in the use of the igniter, the heat and gases from the operation of the engine causes carbon to accumulate on the heated electrode shaft which is deposited as carbon dust at the inner or hot end of the shaft, which carbon dust is comparatively harmless. Adjacent the carbon dust deposit there will accumulate a deposit of caked carbon on said shaft which is quite harmful thereto, and adjacent the deposit of caked carbon there will be a deposit of greasy carbon which is also harmful to the operation of the igniter. Toward the outer end of the shaft away from the electrode and igniter block bearing there will be a deposit of rosin-like material which is also harmful to its operation. Said deposits, other than the carbon dust, prevents the free movement of the electrode shaft in that portion of the bearing, wherein such deposits may accumulate.

It is the main object of this invention to provide a bearing in the igniter block for the movable electrode shaft, so formed as to overcome the difficulties arising from such deposits. This is accomplished by reducing the bearing surface of the block and shaft to a minimum and leaving the block and

shaft in spaced relation to each other where the last three most harmful deposits accumulate.

The full nature of this invention will be understood from the accompanying drawings and the following description and claims.

Fig. 1 is a front elevation of a magneto mounted in connection with a stationary internal combustion engine. Fig. 2 is a section taken on the line 2—2 of Fig. 1. Fig. 3 is a plan view looking down on the igniter.

In the drawings there is shown a portion of an internal combustion engine having a cylinder block 10 mounted on the frame 11 in which the cam shaft 12 operates, causing the cam 13 to revolve and actuate the engine side rod 14. Rigidly secured to the side rod 14 there is a collar 15 upon which is pivotally mounted the actuating arm 16 held in operative position by the spiral spring 17. The end of the actuating arm is in position to engage a lug 18 on the operating mechanism which is transversely mounted on the armature shaft 19 so as to push said lug and cause a partial rotation of said mechanism about said armature shaft. Each end of the mechanism is held in position under spring tension of the springs 20 which are secured at one end to the frame of the magneto at 21. The armature is carried in the housing 22 secured on the base 23 rigidly mounted on the engine, over which the magnets 24 are mounted. The above described mechanism is old and commonly used in magnetos of this type.

Mounted in conjunction with the magneto and rigidly secured in relation thereto there is an igniter block 25 secured in place by the bolts 26, which has drilled therein a hollow sleeve 27, through which an electrode is adapted to extend properly insulated, for connecting the terminal 28 with the igniter 29, the terminal 28 being electrically connected with the armature by the wire 30 and the igniter 29 being rigid with the block 25. The sleeve 27 carries an arm 31 extending parallel with the block 25 and provided with a bearing through which the movable electrode shaft 32 extends, supported at the other end in the bearing formed in the block 25. On the end of said shaft away from said block there is a tripping lever 34 pinned thereon, and between the block 25 and the arm 31 there is a spiral spring 35, having

one end secured to the block 25 and the other end to a collar 36 which is pinned on the shaft by a cotter pin 37. The other end of the shaft 32 is supported in the bearing portion 38 of the block 25. Rigidly secured on the end of said shaft there is an electrode lever 39 having an igniter point thereon adapted to contact with the point of the igniter 29 between which the spark generated 10 passes.

As great difficulty has been had with deposits forming on the shaft 32, and in the bearing of the block 25, the shaft is reduced from the shoulder or bearing surface 40 15 which is narrowed down to about five sixteenths of an inch, or in other words the bearing surface is raised appreciably over the surface of the shaft, the diameter of said shaft being appreciably larger at the bearing point than through the remainder portion of said shaft. A beveled shoulder 41 formed integral with said shaft is adapted to fit snugly in the beveled bearing formed in the portion 42 of said block so as to prevent the exhaust gases from passing through the bearing and depositing carbon therein to a substantial degree. The greater portion of the bearing 38 is enlarged as at 43, whereby as a substantially narrow portion 44, corresponding in width to the bearing surface 40 of said shaft, is reduced in diameter, whereby there will be a snug fitting bearing surface between the bearing portion 44 and the shoulder 40 of the shaft. This bearing construction, permits only carbon dust to collect on the bearing surface, which is harmless, and the caked, greasy and rosin-like material will either escape or form on the non-bearing portion of the shaft, rather than

on the contacting bearing surface as has 40 hereto been the case, so that the shaft 32 will be enabled to properly oscillate. Between the shoulder 41 and the lever 39 there is provided a reduced portion 45 which permits of the proper adjustment and wearing in of the 45 beveled surface of the shoulder 41 in the corresponding bearing surface of the bearing 38.

The invention claimed is:

1. In combination with a magneto and an 50 igniter block therefor, of an electrode shaft, means for oscillating said shaft, an electrode, a reduced bearing in said block adjacent the electrode, adapted to support the shaft, and a shoulder on said shaft forming a bearing 65 surface adapted to register with said reduced bearing, whereby the remaining surface of said shaft will be spaced from the inner surface of said block.

2. An igniter block having a bearing opening therethrough, a support spaced from said block, an electrode shaft extending through said opening and said support, means for oscillating said shaft, an annular bearing portion projecting inwardly from 65 the inner surface of the opening in said block for supporting one end of said shaft therein upon a reduced bearing surface so as to maintain it in spaced relation to the inner surface thereof, and a bearing for said shaft 70 in the support spaced from said block for supporting the opposite end of said shaft, substantially as described.

In witness whereof, we have hereunto affixed our signatures.

BENJAMIN P. REMY.
FRANK I. REMY.
